US0D1047931S

(12) **United States Design Patent** (10) **Patent No.:** **US D1,047,931 S**
Minale et al. (45) **Date of Patent:** **** Oct. 22, 2024**

(54) **SWITCH PLATE**

(71) Applicant: **Buster and Punch Limited**, Stamford (GB)

(72) Inventors: **Massimo Minale**, London (GB); **Iain Dulley**, Winchester (GB)

(73) Assignee: **Buster and Punch Limited**, Stamford (GB)

(**) Term: **15 Years**

(21) Appl. No.: **29/924,140**

(22) Filed: **Jan. 17, 2024**

Related U.S. Application Data

(60) Division of application No. 29/915,559, filed on Nov. 1, 2023, which is a continuation-in-part of application No. 29/876,409, filed on May 22, 2023, now Pat. No. Des. 1,021,813, which is a continuation of application No. 29/745,678, filed on Aug. 7, 2020, now Pat. No. Des. 991,190.

(30) **Foreign Application Priority Data**

CLAIM

The ornamental design for a switch plate, as shown and described.

DESCRIPTION

FIG. 1 is a front view of a switch plate showing the design. FIG. 2 is a side elevation view thereof, with the opposite side view being the mirror image thereof.

FIG. 3 is an isometric view thereof; and,

FIG. 4 is a top plan view thereof, with the bottom plan view being the mirror image thereof.

The broken lines in the drawings illustrate portions of the switch plate that form no part of the claimed design.

1 Claim, 4 Drawing Sheets
